AUTOMATIC DRAIN VALVE FOR COMPRESSED AIR RESERVOIRS

Lloyd L. Hamilton, Oklahoma City, Okla.

Application August 19, 1946, Serial No. 691,627

1 Claim. (Cl. 303—88)

1

My invention relates to air-brake and analogous systems, and particularly to mechanism for eliminating or bleeding off condensation of moisture from such systems.

In most air-pressure actuated brake systems and others in which air is compressed and stored, moisture condenses within the system from the compressed air utilized therein. Such moisture not only causes corrosion of metal parts, but often collects to such an extent in the compressed air reservoir that freezing renders the system inoperative.

The principal object of the present invention is to provide an improved automatic drain valve which eliminates such condensation from the system.

Another object is to provide a moisture ejecting valve mechanism which is simple to install, comparatively cheap to manufacture, and which has few moving parts to become worn or to get out of order.

Other objects will be apparent from the following description when taken in conjunction with the accompanying single sheet of drawings, wherein:

The figure is a schematic view of a portion of a simple vehicle air operated brake system, the bleeder valve mechanism of the present invention being shown in vertical section, and at an enlarged scale.

Like characters of reference designate like parts in those figures of the drawings in which they occur.

In the drawings:

The reference numeral 1 indicates, as a whole, an air compressor unit having its exhaust line 2 connected to an air storage tank 3. The tank 3 has an air outlet line 4 leading through a control valve 5 to an air delivery line 6 which in turn leads to brake operating mechanism, not shown. A foot lever 7 controls operation of the valve 5 and consequently communication between the air lines 4 and 6.

The above described mechanism is usual to conventional air brake systems, and is not a part of the present invention, except that it is in connection with such a system that the present invention is designed to function.

In such air brake systems, moisture from the compressed air in the tank 3 is prone to condense into liquid, and unless bled from the tank, such moisture eventually retards efficient operation of the system. It is the bleeding of such moisture from the tank 3 which the present invention is designed to accomplish.

2

The present invention, per se, includes a bonnet 10 having a central attaching nipple with a through bore 11, and having upper threads 12 whereby it may be installed within an opening 13 in the bottom of the tank 3. The lower portion of the bonnet has an exterior annular flange 14, and therebelow is exteriorly threaded to receive the upper open end of a valve housing 15.

The valve housing 15 has a solid horizontally disposed body portion 16 which forms the bottom of a cavity 17 complementally formed by the housing and the bonnet. The cavity 17 lies at the lower end of the bore 11 and is adapted to receive therethrough any condensation of moisture which may occur in the tank 3. The body portion 16 has a vertical through-bore 18, and therebelow, the housing 15 is completed by the provision of a substantially bell-shaped or annular wall 19 having an outwardly projecting annular flange 20 around its lower open end. The body portion 16 of the housing has a horizontal bore 21 which intersects the vertical bore 18 and the walls 19 have a plurality of outlet perforations 30.

Attached to the flange 20 of the housing by bolts 22, is a metal cup 23 having a threaded opening 24 in one wall. A flexible diaphragm 25 has its continuous edge portion impinged between the cup 23 and the flange 20, and is held rigidly in place by the tightened bolts 22. The bell-shaped wall 19 and the cup 23 complementally form a chamber within which the central portion of the diaphragm may work vertically, and which is hermetically divided horizontally by the diaphragm into upper and lower compartments. The two compartments are respectively indicated by the reference numerals 26 and 27.

Slidably disposed vertically within the two vertical bores 11 and 18, but of considerably less diameter than the bore 11, is provided a reciprocatable valve stem 28. The upper end or section of the valve stem is preferably tapered, and the lower end thereof extends downwardly into the compartment 26 and is threadedly anchored within a socket member 29 which may be attached by any suitable means to the upper surface of the imperforate diaphragm 25. A suitable helical compression spring 31 is provided within the chamber 26 and around the valve stem 28, and acts to normally maintain the diaphragm and stem at the lower end of their permitted travel. A suitable hydraulic packing is provided in the upper end of the bore 18 and around the stem 28.

Within the cavity 17, the valve stem 28 is provided with a rigidly mounted ball valve 32 which is adapted to normally seat in the upper end of the bore 18 and close the same. The spring 31 acts to hold the ball 32 in said seated position under normal conditions, and air pressure from the tank 3 therefore is normally present in the cavity 17. A removable valve seat member 33 may be provided in the upper end of the bore 18, if desired.

Should the diaphragm 25 be forced upwardly, and consequently raise the valve stem 28, the ball 32 will likewise be moved upwardly to close the lower end of the bore 11. Such movement will, of course, open the bore 18 and will thereby open communication between the cavity 17 and the atmosphere around the device through the bores 18 and 21. A removable valve seat 34 may, if desired, be provided in the lower end of the bore 11.

It is thought to be obvious that under normal conditions, and during the time the ball valve 32 is in its lower seated position, any moisture which might normally accumulate in the tank 3 will gravitate to and be retained within the cavity 17, and as stated hereinabove, such moisture will be under such pressure as is present in the tank 3 due to action of the compressor 1. Should the ball valve be forced to its upper seated position, any fluid, either liquid or air, then residing in the cavity 17 will expand and exhaust from the cavity through the bores 18 and 21 to the open air. Therefore, should the valve 32 be moved upwardly with sufficient frequency, moisture condensation in the tank 3 would be entirely eliminated, or would at least be retarded to the extent that the cavity 17 would fully accommodate such condensation.

As a means for intermittently reciprocating the ball valve 32, the air line 6 is provided with a branch-line 35 leading to the opening 24 in the cup 23. Every time the brake pedal 7 is moved to open the valve 5, compressed air will travel from the line 6 through the branch-line 35 to the chamber 27 beneath the diaphragm 25. Due to the fact that the exposed area of the diaphragm is greater than the upper area of the ball valve 32, the diaphragm will be flexed upwardly, and will consequently move the valve stem and ball upwardly. The result is that accumulated moisture is bled from the cavity 17 every time the brake system is operated. This is normally often enough to take care of moisture condensation under ordinary weather conditions, but any amount of condensation may be exhausted by merely actuating the foot pedal 7 a few times in rapid succession.

It is also pointed out that the bleeding mechanism could well be located at any point in the air brake system where moisture condensation is likely to occur, and that if desired separate valve actuating controls, other than the pedal 7, could well be provided. The improved drain valve has been found to be highly effective in removing condensed water, oil and sludge that accumulate in the air tanks or reservoirs on motor trucks,

and buses and other automotive vehicles having air brakes, but it may be used on the air storage tanks of service station compressors and in other ways.

5 Obviously the invention is susceptible to some change or alteration without defeating its practicability, and I therefore do not wish to be confined to the preferred embodiment shown in the drawings and described herein, further than I 10 am limited by the scope of the appended claim.

I claim:

A valve of the character set forth comprising a casing body formed with a horizontal portion having a central vertical bore, a cylindrical wall 15 concentric with bore and extending upwardly from said body portion to form a drain compartment, and an annular wall concentric with said bore and extending downwardly from said body portion, a bottom casing section removably secured to the lower edge of said annular wall and having a pressure-fluid inlet, a flexible imperforate diaphragm having its edge clamped between said annular wall and said bottom section to seal said inlet from said bore, a top casing 20 section removably secured to the upper edge of said cylindrical wall to close said drain compartment, said top section having a central vertical bore axially aligned with the bore in said body portion and a drain-inlet attaching nipple through which said bore extends, the bottom of said top section and the top of said body portion being provided with opposed valve seats concentric with said bores, a valve in said drain compartment to alternately engage said seats, an upper stem projecting from the top of said valve and slidable in the bore of said top section, a lower stem projecting from the bottom of said valve and slidable in the bore of said body portion, said lower stem having an externally screw 25 threaded lower extremity terminating above said diaphragm, a removable socket member engaged with the threaded extremity of said lower stem, and a coil spring surrounding said lower stem between said socket member and said body portion to normally hold said valve closed on the seat on said body portion, said casing having means permitting the escape of the contents of said drain compartment through the bore in said body portion when said valve is lifted from the last-mentioned seat.
